UNITED STATES PATENT OFFICE.

AUGUST CARLEWITZ, OF NEWARK, NEW JERSEY.

DESIGN FOR A CORNICE.

SPECIFICATION forming part of Design No. 21,579, dated May 24, 1892.

Application filed February 4, 1892. Serial No. 420,365. Term of patent 7 years.

To all whom it may concern:

Be it known that I, AUGUST CARLEWITZ, a citizen of the United States, residing at Newark, in the county of Essex and State of New Jersey, have invented and produced a new and original Design for Cornices, of which the following is a specification, reference being had to the accompanying drawings, showing a part thereof.

10 Figure 1 is a front elevation of a cornice, showing my design. Fig. 2 is an end view at *b*, showing the shape of the cornice.

15 The leading features of my design consist in raised figures of cherubs and flowers, the outlines of which when viewed in elevation, as in Fig. 1, will fall principally within the cove of the cornice.

A is the central portion or cove of the cor-

nice, which is convex in its general contour, and *B* and *C* are respectively the upper and lower beads or moldings above and below the cove. In the cove are the raised figures of cherubs *D* and *E*, clasping a vine *H*, on which are bunches of flowers *I*, *J*, *K*, and *L*, ribbons or streamers *c* and *d* being twined around the figures and vine. Near each figure or cherub there is a spray of leaves *e* and *f*, which extend over the upper and lower bead or molding.

20 What I claim is—

25 The design for a cornice, substantially as shown and described.

AUGUST CARLEWITZ.
